SHIRT

W. Vincent Thelander, Toledo, Ohio

Application January 18, 1951, Serial No. 13,849

Term of patent 14 years

(Cl. D3—25)

To all whom it may concern:

Be it known that I, W. Vincent Thelander, a citizen of the United States, residing at Toledo, State of Ohio, have invented a new, original, and ornamental Design for a Shirt, of which the following is a specification, reference being had to the accompanying drawing, forming a part hereof.

Fig. 1 is a front view of a shirt showing my new design.

Fig. 2 is a fragmentary top plan view thereof.

The back of the shirt is plain or conventional.

I claim:

The ornamental design for a shirt, as shown and described.

W. VINCENT THELANDER.
